UNITED STATES PATENT OFFICE.

GARDINER F. BADGER, OF EAST ORANGE, NEW JERSEY, ASSIGNOR TO
PULSOMETER STEAM PUMP COMPANY, OF NEW YORK, N. Y.

STEAM VACUUM-PUMP.

SPECIFICATION forming part of Letters Patent No. 238,548, dated March 8, 1881.

Application filed November 19, 1880. (No model.)

To all whom it may concern:

Be it known that I, GARDINER F. BADGER, of East Orange, in the county of Essex and State of New Jersey, have invented a new and 5 useful Improvement in Steam Vacuum-Pumps, of which the following is a specification.

This invention relates to that class of steam vacuum-pumps called "pulsometers," which are operated by steam-pressure brought directly upon the liquid as the forcing element, while the subsequent condensation of the steam furnishes the lifting power to supply the pump.

The invention consists of an improved valve-seat designed for the induction and eduction 15 water-ways, and of improved devices for holding the valve-seats and valve-guards in place.

The invention is an improvement on the pump patented by Charles H. Hall, September 24, 1872.

Figure 1 is a vertical sectional front elevation of the pump, showing the induction-valve seat, valve, and guard in section on one side, and in full elevation on the other side. Fig. 2 is a perspective view of the reverse of the 20 pump with parts removed and broken away to exhibit other parts. Fig. 3 is an enlarged sectional elevation of eduction-valve seats, valve-guard, valve, and holding devices in position. Fig. 4 is an enlarged sectional elevation, showing an induction-valve-seat seat, valve-guard, and valve, and position of holding device.

Similar letters of reference indicate corresponding parts.

The pump consists, principally, of the bottle-shaped chambers A A, joined together side by side, and having tapering necks bent toward each other, to which is attached, by means of a flange-joint, B, a cap, B', in which is a continuous passage from each cylinder leading to one common upright passage, into which a small ball, C, is fitted, so as to oscillate with a slight rotary motion between seats formed in the junction. The bottle-shaped chambers 35 A A terminate at their bases in chambers or passages D' D', which also connect, by means of openings a a, with the vertical induction-passage D, which openings a a are so formed that the induction-valves E E and their seats 40 F F, constructed so as to sustain the said

valves, may be easily inserted. The eduction passage or chamber H, which is common to both chambers A A, is also constructed so that in the openings or chambers b b, that communicate with each cylinder or chamber A A, are placed valve-seats G G, fitted for the reception of the same style of valves E E as in the induction-passages. J represents the vacuum-chamber, cast with and between the necks of chambers A A, and connecting only with the 55 induction-passage D below the valves E E. All these various parts, excepting the cap B, ball C, and valves and valve-seats, are cast in one piece of metal.

The faces of the chambers D' H are closed 60 by means of flanged covers I I, the flanges of which correspond with flanges on the chamber-faces on the pump-body, and they are united by means of suitable screw-bolts and nuts.

The openings a a between the induction-passage D and chambers A are formed with upward-flaring sides c c, for receiving the valve-seats F F, and the openings b b between the eduction passage or chamber H and chambers A A are also formed with like upward-flaring 70 sides d d, for receiving the valve-seats G G.

In pulsometer-pumps as at present constructed the sides of the induction and eduction chambers have formed in them recessed ways for receiving the valve-seats, which ways 75 are V-shaped at their bases.

In order to get the receiving-seats for the valve-seats true it is necessary to cast the former on chills introduced into the mold. It is found, however, in the construction of pumps 80 with the recessed V-shaped ways, that there is great difficulty in withdrawing the chill even under the best conditions, and that the said chill is frequently withdrawn only at the cost of the chill, that has to be recast, while sometimes it is impossible to remove the chill without breaking the pump. To avoid these difficulties the upward-flaring sides c d are substituted for the ordinary recessed V-shaped ways. With this construction the "chills" are 85 readily knocked out or fall out with cores of the casting.

The valve-seats F G, respectively, have downward beveled or sloping edges to conform to their seats c d, and are provided with open- 90

ings *f f* for the free passage of water, and when in place are supported also on simple packing-rings *gg*, that rest on the annular shoulders *h h*, formed below the sides or seats *c d*.

5 The valves *E E* are formed, preferably, of vulcanized rubber of suitable thickness, are circular in form, and of sufficient diameter to cover the perforations *f f* in the valve-seats *F G*.

K K' represent the valve-guards—designed to 10 prevent the valves *F G* from opening too far—of hemispherical shape and perforated, as shown at *k*, to permit the water to escape without undue pressure between said guards *K K'* and valves *F G*, as the latter open, and the 15 guards *K* over the induction-passages *D* are each provided with an apical stud, *m*, that engages in a corresponding socket in the valve-seat *E*.

After an induction-valve seat, *F*, with its 20 valve *E* and valve-guard *K*, is in place, they are rigidly secured by means of a rod, *L*, whose lower end is inserted into a central socket in the guard *K*, at right angles to the face of the valve-seat *F*, while the upper end of said rod 25 *L* is held by a set-screw, *M*, that is inserted diagonally through a side of a chamber, *A*, so that its point shall press axially upon the end of said rod *L* with whatever force may be desired. By this device an induction-valve seat, 30 valve, and valve-guard are firmly held by but one set-screw and in such a manner that the pressure of the valve-seat upon its seat can be adjusted with the greatest ease and celerity, thereby having a great advantage over those 35 constructions wherein several set-screws are required for the same purpose.

The induction-valve seats *G*, with their valves *E* and valve-guards *K'*, are secured in place by means of bolts *O*, that are entered from the 40 outside through the openings or chambers *b b*, and have their ends passed through the centers of the valve-seats *G* and screwed into the

guards *K'*, as shown in Figs. 2 and 3, said bolts *O* having countersunk heads to fit into corresponding countersinks in the shells of the chambers *b b*, and having their heads extended outward and squared for the convenience of applying a wrench for tightening them. 45

By the improved devices herein described, the cost of constructing a pump is very materially reduced, and the pump is rendered more durable and less liable to get out of order, and its operation is perfect as far as these parts are concerned. 50

Having thus described my invention, I claim 55 as new and desire to secure by Letters Patent—

1. In the construction of a steam vacuum-pump, the combination, with the induction-chambers *D' D'* and eduction-chambers *H*, of 60 the upward-flaring valve-seat seats *c d* and detachable valve-seats *F G*, respectively having corresponding downward beveled edges, all arranged substantially as herein shown and described. 65

2. In a steam vacuum-pump, as a means for holding the induction-valve seats, valves, and valve-guards in place, the combined rod *L* and set-screw *M*, substantially as herein shown and described, said rod and screw being set in line 70 at right angles to the face of the valve-seat, as set forth.

3. In a steam vacuum-pump, the combination, with the valve-seat *G*, valve *E*, and screw-tapped valve-guard *K'*, of the screw-bolt *O*, 75 substantially as herein shown and described, said bolt being entered through the shell of the pump and screwed at right angles into the valve-guard, as set forth.

GARDINER F. BADGER.
